Primary Examiner — Kelley Donnelly(74) Attorney, Agent, or Firm — Dave Alan Lingbeck(57) CLAIM

The ornamental design for a food and beverage tray head gear, as shown and described.

DESCRIPTION

FIG. 1 is a top perspective view of a food and beverage tray head gear showing my new design.

FIG. 2 is bottom perspective view of the food and beverage tray head gear.

FIG. 3 is a side elevation view of the food and beverage tray head gear with all side elevation views being mirror images thereof.

FIG. 4 is a top plan view of the food and beverage tray head gear.

FIG. 5 is a bottom plan view of the food and beverage tray head gear; and,

FIG. 6 is cross sectional view of the food and beverage tray head gear.

The broken lines showing is included for the purpose of illustrating environment and forms no part of the claimed design.
